(57) **CLAIM**

I claim the ornamental design for a cold brew coffee maker, as shown and described.

DESCRIPTION

FIG. 1 is a top, front perspective view of a cold brew coffee maker of the present invention.

FIG. 2 is a front view of the cold brew coffee maker depicted in FIG. 1.

FIG. 3 is a left, side view of the cold brew coffee maker depicted in FIG. 1.

FIG. 4 is a rear view of the cold brew coffee maker depicted in FIG. 1.

FIG. 5 is a right, side view of the cold brew coffee maker depicted in FIG. 1.

FIG. 6 is a top view of the cold brew coffee maker depicted in FIG. 1; and,

FIG. 7 is a bottom view of the cold brew coffee maker depicted in FIG. 1.

The broken lines in the drawings illustrate environment that form no part of the claimed design and portions of the cold brew coffee maker that form no part of the claimed design.

1 Claim, 7 Drawing Sheets
